(57) **CLAIM**

We claim the ornamental design for a sponge cleaning and disinfecting device, as shown and described.

DESCRIPTION

FIG. 1 is an isometric view of the sponge cleaning and disinfecting device showing the new design.

FIG. 2 is a front elevation view showing the new design.

FIG. 3 is a rear elevation view showing the new design.

FIG. 4 is a left side elevation view showing the new design.

FIG. 5 is a right side elevation view showing the new design.

FIG. 6 is a plan view showing the top of the new design; and,

FIG. 7 is a plan view showing the bottom of the new design.

The broken lines shown in the drawings represent portions of the sponge cleaning and disinfecting device which form no part of the claimed design.

Apparatus for compressing and immersing a sponge in liquid disinfectant.
